CLAIM

We claim the ornamental design for a mobile phone case, as shown and described.

DESCRIPTION

FIG. 1 is a front perspective view of a mobile phone case according to a first embodiment;

FIG. 2 is a rear perspective view of a mobile phone case according to a first embodiment;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a partial enlarged view of the circled portion "9" of FIG. 1;

FIG. 10 is a front perspective view of a mobile phone case according to a second embodiment;

FIG. 11 is a rear perspective view of a mobile phone case according to a second embodiment;

FIG. 12 is a front view thereof;

FIG. 13 is a rear view thereof;

FIG. 14 is a left side view thereof;

FIG. 15 is a right side view thereof;

FIG. 16 is a top view thereof;

FIG. 17 is a bottom view thereof; and,

FIG. 18 is a partial enlarged view of the circled portion "18" of FIG. 10.

The dash-dash broken lines depict portions of the mobile phone case in which the design is embodied that form no part of the claimed design. The dot-dash broken line circles and lead lines in FIGS. 1, 9, 10 and 18 are included for the
